UNITED STATES PATENT OFFICE.

GEORGE W. VAN TINE, OF BAYONNE, NEW JERSEY.

MOLDING-PRESS.

SPECIFICATION forming part of Letters Patent No. 569,690, dated October 20, 1896.

Application filed October 25, 1893. Serial No. 489,125. (No model.)

To all whom it may concern:

Be it known that I, GEORGE W. VAN TINE, a citizen of the United States, residing at Bayonne, in the county of Hudson and State 5 of New Jersey, have invented certain new and useful Improvements in Molding-Presses, of which the following is a specification, reference being had therein to the accompanying drawings.

10 My invention relates to that class of molding-presses provided with swinging sand-boxes containing the patterns and carrying the half-flasks, in which latter the molds are formed by the pressing operation, the object 15 of my invention being to provide mechanical means for swinging or otherwise moving the said boxes in and out of the press, thereby lightening the labor of working the presses, (particularly in those presses having large 20 heavy sand-boxes,) as well as expediting the work. To this end I provide a molding-press with horizontal pressure-cylinders in which work pistons connected to the movable or swinging sand-boxes in such manner that by 25 admitting water or other pressure fluid to the said pressure-cylinders the sand-boxes may be swung or otherwise moved in or out of the press.

In the accompanying drawings, Figure 1 is 30 a side elevation, partly in section, of a molding-press embodying my invention. Figs. 2 and 3 are plan and cross-sectional views, respectively, of the same on a larger scale than Fig. 1. Fig. 4 is a detail plan view of the 35 pressure-cylinder and rack for operating the swinging sand-boxes.

A denotes the base of the press, and B a table mounted on said base and serving as a support for the ram-cylinders C, in which 40 work the plungers D, carrying the platens d, said cylinders having supply and discharge pipes c, through which the pressure fluid enters and leaves the cylinders. The press-head E is supported by suitable posts or stand- 45 ards F, surrounded by sleeves G, having arms g, carrying the swinging sand-boxes H, which support the half-flasks H', in which the molds are formed.

The press herein shown is a large one having 50 great capacity, there being four posts or standards F, each surrounded by a sleeve G, and each sleeve carries a double sand-box.

Mounted on arms or brackets a, extending outward from the base A, are horizontal pressure-cylinders I, within which work pistons J, having rods k, provided with double racks K, meshing with gears g', attached to the sleeves G. The cylinders I are provided with inlet and outlet pipes i, extending to any suitable source of pressure-supply.

55 From the foregoing it will be obvious that by admitting the water or other pressure medium to one end or the other of said cylinders I the pistons J therein will be moved to operate the racks K, connected by the gears 60 g' to the sleeves G, thereby swinging the sand-boxes H in or out of the press, as may be desired, the double racks herein shown each swinging two double sand-boxes in or out of the press, said double sand-boxes moving 70 around in opposite directions. While the two double sand-boxes operated by one of the racks K are in pressing position in the press, the other two double boxes are thrown outward in position for removing the molds and 75 refilling the sand-boxes and half-flasks.

I do not wish to be understood as limiting my invention to the details herein shown, as it is obvious that these may be widely varied without departing from the spirit of my invention. For example, the sand-boxes might 80 be sliding ones instead of being carried by swinging arms, and might therefore be operated directly from the plunger-cylinders instead of through the medium of the racks and 85 gears; also, single racks might be used to move a single sand-box or a single set thereof instead of the double racks for simultaneously 90 operating two double sand-boxes; and other variations within the province of mechanical skill might also be made in the details of my invention.

Having thus described my invention, I claim and desire to secure by Letters Patent—

95 1. In a molding-press, the combination with pressure-cylinders, pistons working therein and racks operatively connected with said pistons, of swinging sand-boxes and gears engaged by said racks and operatively connected with said sand-boxes.

2. In a molding-press, the combination with the posts or standards thereof, of sleeves surrounding said posts or standards and provided

with gears, sand-boxes carried by arms extending from said sleeves, pressure-cylinders, pistons working in said cylinders and racks engaging said gears and operated from said pistons.

5. In a molding-press, the combination with

the posts or standards F, of the sleeves G surrounding said posts and provided with the gears g' and the arms g, sand-boxes H supported by said arms, pressure-cylinders I, pis-

tons J working therein, racks K engaging said gears, and rods l connecting said racks with said pistons.

In testimony whereof I affix my signature in presence of two witnesses.

GEORGE W. VAN TINE.

Witnesses:

HENRY CALVER,

J. F. JAQUITH.
